UNITED STATES PATENT OFFICE.

ROYAL L. WALES, OF KNOXVILLE, TENNESSEE.

STEAM-TRAP.

No. 895,702.

Specification of Letters Patent. Patented Aug. 11, 1908.

Application filed August 2, 1907. Serial No. 386,801.

To all whom it may concern:

Be it known that I, ROYAL L. WALES, a citizen of the United States of America, residing at Knoxville, in the county of Knox 5 and State of Tennessee, have invented a new and useful Steam-Trap, of which the following is a specification.

My invention relates particularly to steam traps applicable to steam heating systems. 10 The object of the invention is to produce a sensitive and efficient trap allowing the passage of cold water, hot water, and air without allowing the passage of steam.

In the accompanying drawings, Figure 1 is 15 an upright section along the axis of a trap embodying my improvement; Fig. 2 is a plan of the same apparatus, a portion being broken away.

Referring to said drawings, A is the casing 20 of the trap. This is, in the main, cylindrical in form, and has a fitting, 1, at its lower end for the attachment of a waste pipe, and has a screw-threaded opening at the top to receive a cap, 2. Just below the cap is a branch 25 connection, B, to which a pipe, C, may be joined in any suitable manner. Near the lower portion of the casing is a horizontal partition, 3, secured by screw-threading to the interior of the casing. For convenience 30 in description, the space within said casing above said partition is herein termed the "condensation chamber." At the center of said partition is a port or outlet, 3^a, around which is formed a valve seat, 4, which seat is 35 adapted to receive a half-spherical valve, 5. Said valve is herein termed the "main valve." Below said valve is a cross-bar or bridge, 6, into which a short upright tubular column or spindle, 7, is screw-threaded. 40 The passage through said spindle has a contraction, 8, at its lower end, to permit the passage of only a small stream of water or air. Above said spindle is a vertically-expansible pressure chamber, 11, the lower wall 45 of which is secured to said spindle and the upper wall of which is secured to the lower end of a similar upright tubular spindle, 9, seated in the valve, 5. Both of said walls are centrally open so that there is free communication from the condensation chamber 50 through the spindle, 9, the pressure chamber, 11, and the spindle, 7. In other words, the pressure chamber has an inlet through the spindle, 9, and an outlet through the spindle,

7. But, since, as already herein described, 55 the lower portion of the spindle, 7, has the contraction, 8, it follows that the pressure chamber has an inlet larger than its outlet. In the upper end of the bore of the spindle, 9, is a valve seat, 10.

From the foregoing it will be seen that 60 there are two outlets through the cross-partition, 3, by which water and air may pass out of the condensation chamber when said outlets are open. As already explained, the 65 larger of said openings, 3^a, may be closed by the valve, 5. The second of said outlets, which is through said valve, 5, may be closed by the float-controlled valve to be next described.

In the condensation chamber, the space 70 above the cross-partition, 3, is a float member, 13, on the lower portion of which is a valve, 14, adapted to rest on the valve seat, 10, when said float member is subjected to 75 a temperature higher than the ordinary temperature of a room and when the amount of water in said casing, A, is not sufficient to lift or float said member. Whenever said valve, 14, rests upon its seat, communication 80 between the condensation chamber and the interior of the pressure chamber, 11, is cut off. At the upper end of the float member, 13, is an upright stem, 15, which extends 85 slidably through an aperture, 16, in the open cross-partition, 18. Upon the upper end of the stem, 15, is a head, 17, which is adapted to support the float member, 13, under certain conditions as will be hereinafter described. Said float member is thermally 90 expansible in the upright direction, in order that the distance between the head, 17, and the valve, 14, may be varied by thermal variation. One of the ways for making said member thermally expansible is to make it 95 hollow, as shown in the drawings, one or both of the heads being made flexible and the interior space being partially or entirely filled with a liquid, vapor, or gas adapted to expand under temperature higher than the 100 ordinary temperature of a room and lower than the heat of steam, whereby said heads are, during the presence of such temperature, pressed from each other so as to effect a sufficient lengthening between the head, 17, and the valve, 14, to permit the latter to extend 105 downward and bear upon the valve seat, 10. A conical screen, 19, rests upon the open

cross-partition, 18, to hold back such solid matter as might interfere with the proper action of the valves, 14 and 5.

The operation is as follows: When the apparatus is cold and empty and the float member, 13, is sufficiently contracted to cause the head, 17, to engage the cross-partition, 18, and suspend the float member from said partition, the valve, 14, on the lower portion of 13 said float member standing above the valve seat, 10, and leaving passage for air and water through the spindle, 9, the pressure chamber, 11, and the spindle, 7, the contraction, 8, in the lower portion of the spindle, 7, 15 allowing the passage of only a limited quantity of such air and water. Under such condition, the pressure in the condensation chamber, in the pressure chamber, 11, and in the space below the contraction, 8, in the 20 spindle, 7, is substantially the same. If steam is now driven toward the pipe, C, and the quantity of air and cold water entering the trap as a result of such driving of steam is not in excess of the capacity of said contraction, 8, said air and water will flow 25 through the spindle, 9, pressure chamber, 11, and spindle, 7, indefinitely. But if the quantity of air and water, or either, is more than will readily pass the contraction, 8, the 30 chamber, 11, becomes filled with such water or air under pressure, whereby said chamber is expanded so as to lift the main valve, 5, from its seat and allow the passage of said air or water through said valve as well as 35 through the valve, 14. And since the valve, 5, is much larger than the contraction, 8, there is a relatively rapid flow of air or water through said main valve, 5, and there may, therefore, be such a rapid decline in pressure 40 within the condensation chamber and the pressure chamber, 11, as to allow the latter chamber to contract and restore the valve, 5, to its seat, there to remain until pressure is again established in the pressure chamber in 45 the same manner as has already been described. In this way the operation proceeds, the float member remaining suspended from the head, 17, and the valve, 14, being held above its seat and constantly allowing 50 the passage of both air and cold water through the spindle, 9, pressure chamber, 11, and spindle, 7. But this condition changes when the cold water gives way to hot water and the latter, by its heat, causes the expansion 55 of the float member, 13, to such degree as to cause the valve, 14, to press upon the seat, 10. Then the flow of water and air from the space above the valves, 14 and 5, is entirely cut off, for now both of said valves 60 are upon their seats. Therefore the water will accumulate in the space above the cross-partition, 3, (the condensation chamber) and will continue to so accumulate until it has risen far enough around the float member, 13, 65 to create a buoyancy sufficient to lift the float

member, the stem, 15, sliding in the aperture, 16, until the valve, 14, is lifted sufficiently to permit the passage of water. Then such water flows downward through the spindle, 9, the pressure chamber, 11, and the spindle, 7; and if such flow is limited to the capacity of the contraction, 8, it continues indefinitely; but if the flow passing the valve, 14, is in excess of the capacity of said contraction, the pressure chamber, 11, becomes filled and expands so as to raise the valve, 5, from its seat and allow a relatively rapid flow of water through said valve. Thus the height of the water in the condensation chamber is rapidly reduced and the float member allowed to descend until the valve, 14, bears upon its seat, 10, whereby pressure in the pressure chamber, 11, is cut off and the latter promptly contracts and allows the valve, 5, to return to its seat. Now both the valves, 14 and 5, are again closed, and they will so remain until the water in the condensation chamber again rises sufficiently to lift the float member so that the valve, 14, is again raised. The above supposes that the pressure above 90 said cross-partition, 3, is greater than below said partition, and such is usually the case. Usually the pressure below said partition is very slight, and in some cases there is a partial vacuum below said partition. The float 95 member always descends before all the water has escaped through the valves, 14 and 5; and therefore the two valves are constantly covered with water and thus sealed against the passage of steam. This is to be regarded 100 as the normal condition of the apparatus.

The expansibility of the float member, 13, is used after the operation has been established, after the passage of all the cold air and cold water. Then the arrival of the hot water produces expansion of said member and such expansibility is then and thereafter used to cause the closing of the valve, 14, when there is an absence of enough water to bodily lift said float member. And such 110 quantity of water is treated as abnormal and is at once reduced by flow through the valve, 14, and immediately thereafter also through the valve, 5. And it will be observed that the trap will always automatically open upon 115 cooling of the apparatus. For if the supply of steam should cease and the water in the condensation chamber consequently become cool, the float member, 13, would contract and become suspended by its head, 17, the 120 valve, 14, being lifted from its seat and leaving a free passage for the outflow of such water through the pressure chamber. Then the apparatus is empty and not subject to freezing and consequent injury.

The weight and dimensions of the float member, 13, and the area of the valve, 14, and the volume of the float member must be so proportioned as to cause sufficient buoyancy before the float member is covered with 130

water and the increase of buoyancy terminated. And it is to be observed that the area of the walls of the pressure chamber must be greater than the area of the main valve, 5, in 5 order that the lifting power applied within said chamber may be greater than the downward pressure upon said valve.

I claim as my invention:

1. In a steam trap, the combination of a 10 condensation chamber, a pressure chamber, said chambers being connected by a normally-closed valved passage the valve of which is submerged when closed and said pressure chamber having an outlet smaller 15 than said passage, and a main valve located in the wall of said condensation chamber and in operative relation with said pressure chamber for unseating by pressure of fluid flowing from said condensation chamber 20 through said passage into said pressure chamber, a thermally-expansible float member in operative relation with said first mentioned valve to lift the latter from its seat when said float member is cold or when said member 25 is floated by water in the condensation chamber and to press said valve upon its seat and close said passage when said member is heated and there is not sufficient water in the condensation chamber to float said 30 member, substantially as described.

2. In a steam trap, the combination of a condensation chamber, a pressure chamber, a main valve in the wall of said condensation chamber, a member supporting said main 35 valve and joined to a movable wall of said pressure chamber and having a valved passage communicating with said pressure chamber said pressure chamber having an outlet smaller than said passage, said main valve and 40 the valve of said passage being normally submerged in water, and a thermally-expansible float member in operative relation with the valve of said passage to lift said valve from its seat when said float member is cold or 45 when said member is floated by water in the condensation chamber and to press said valve upon its seat and close said passage when said member is heated and there is not

sufficient water in the condensation chamber to float said member, substantially as de- 50 scribed.

3. In a steam trap, the combination of a casing, a horizontal partition in the lower portion of said casing, a main valve seated in said partition, a pressure chamber located 55 within said casing below said partition and having an outlet, a spindle seated upon said pressure chamber and extending through said main valve and supporting the latter and having a valved passage communicating 60 with said pressure chamber and larger than said outlet, and a thermally-expansible float member located above said partition in operative relation with the valve of said valved passage to lift said valve from its seat when 65 said float member is cold or when said member is floated by water and to press said valve upon its seat and close said passage when said member is heated and there is not sufficient water above said partition to float 70 said member, substantially as described.

4. In a steam trap, the combination of a casing, a horizontal partition in the lower portion of said casing, a bridge below said partition, a main valve seated in said partition, a pressure chamber secured upon said bridge and having an outlet, a spindle secured upon said pressure chamber and extending through said main valve and supporting the latter and having a valved passage communicating with said pressure chamber and larger than said outlet, and a thermally-expansible float member located above 75 said partition in operative relation with the valve of said valved passage to lift said 80 valve from its seat when said float member is cold or when said member is floated by water and to press said valve upon its seat and close said passage when said member is heated and there is not sufficient water above said partition to float said member, substantially as 85 described.
